United States Patent Office.

D. S. BUTLER, OF OTTERVILLE, MISSOURI.

Letters Patent No. 96,083, dated October 26, 1869.

IMPROVEMENT IN BUCKLES.

The Schedule referred to in these Letters Patent and making part of the same

To all whom it may concern:

Be it known that I, D. S. BUTLER, of Otterville, in the county of Cooper, and State of Missouri, have invented a new and improved Buckle; and I do hereby declare that the following is a full, clear, and exact description thereof, which will enable others skilled in the art to make and use the same, reference being had to the accompanying drawings, forming part of this specification.

Figure 1 represents a face view of my improved buckle, showing it applied.

Figure 2 is a longitudinal section of the same.

Similar letters of reference indicate corresponding parts.

This invention relates to a new self-fastening buckle, which can readily connect two straps, without sewing or other tedious process.

The buckle is made of two pieces, of the frame A, and the tongue-piece B.

The frame consists of two side-pieces, *a a*, which are connected at all four corners by cross-pieces *b b*, and near the middle by another cross-piece, *c*.

The tongue-plate B is pivoted transversely between the plates *a a*, by a pivot, *h*, and has its outer or swinging end provided with teeth, *d*, which are opposite to teeth *e*, on the bar *c*.

The plate B has two tongue-pieces or pins, *f g*, one projecting from each side, as shown.

The device is applied as follows:

One strap, *C*, is fitted through one end of the buckle, between the bars *b b*, at such end, and is drawn over the bar *c*, and placed upon the teeth of the same. The plate B is then swung down to fit the pin *f*, through an aperture of the strap *C*, and to also, with its teeth, clamp the end of such strap, as shown in fig. 2.

The other strap, *D*, is fitted through the other end of the buckle, between the bars *b b*, and locked over the tongue-piece *g*, the end being drawn out between the bars *b b*, above the strap *C*, as shown.

The two belts are thus securely locked together.

By means of this buckle, every person is enabled to make a bridle, or other piece of harness, without the aid of experts, and without difficult process.

Having thus described my invention,

I claim as new, and desire to secure by Letters Patent—

1. A buckle, having a tongue-plate, B, with teeth *d* on its swinging end, combined with a bar, *c*, having corresponding teeth affixed thereto, as set forth.

2. A pivoted tongue-plate, B, having teeth *d*, and two pins, *f g*, in combination with frame A, having toothed bar *c*, and the recesses and perforations, shown and described.

D. S. BUTLER.
